UNITED STATES PATENT OFFICE.

ADOLPH PETZOLD, OF PHILADELPHIA, PENNSYLVANIA, ASSIGNOR TO JOHN H. BROMLEY AND EDWARD BROMLEY, OF SAME PLACE.

DESIGN FOR A RUG.

SPECIFICATION forming part of Design No. 28,833, dated June 7, 1898.

Application filed April 30, 1898. Serial No. 679,403. Term of patent 3½ years.

To all whom it may concern:

Be it known that I, ADOLPH PETZOLD, a citizen of the United States, residing in the city of Philadelphia, State of Pennsylvania, have
5 invented and produced a certain new and original Design for a Rug, of which the following is a full, clear, and exact description, reference being had to the accompanying drawing, forming a part of this specification.
10 My invention relates to the surface ornamentation of a woven fabric, and as employed by me and shown in the drawing is applied to a "Smyrna" rug. Its distinguishing features are rectangular parallel inner and outer borders a and b, with contiguous or connected 15 floral or leaf figures c between such borders, the field center having a central figure d with a series of leaf figures surrounding it.

I claim as new—

The design for a rug substantially as shown 20 and described.

In testimony whereof I have hereunto affixed my signature this 25th day of March, A. D. 1898.

ADOLPH PETZOLD.
